DESIGN FOR A STROLLER OR SIMILAR ARTICLE

Sadye Joy Wallace, New York, N. Y.

Application July 23, 1947, Serial No. 140,473

Term of patent 7 years

(Cl. D14—3)

To all whom it may concern:

Be it known that I, Sadye Joy Wallace, a citizen of the United States, residing at New York, in the county of New York and State of New York, have invented a new, original, and ornamental Design for a Stroller or Similar Article, of which the following is a specification, reference being had to the accompanying drawing, forming part thereof.

In the drawing:

Fig. 1 is a front view of a stroller, showing my new design;

Fig. 2 is a side view thereof, and

Fig. 3 is a perspective view of the stroller as seen from the front and one side thereof.

I claim:

The ornamental design for a stroller or similar article, substantially as shown.

SADYE JOY WALLACE.
